UNITED STATES PATENT OFFICE.

JOHN E. SWEET, OF SYRACUSE, NEW YORK.

STEAM AND WATER SEPARATOR.

SPECIFICATION forming part of Letters Patent No. 532,296, dated January 8, 1895.

Application filed August 27, 1894. Serial No. 521,359. (No model.)

To all whom it may concern:

Be it known that I, JOHN E. SWEET, of Syracuse, in the county of Onondaga, in the State of New York, have invented new and useful Improvements in Steam and Water Separators, of which the following, taken in connection with the accompanying drawings, is a full, clear, and exact description.

This invention relates to steam and water separators.

My object is to produce an apparatus for separating entrained water in steam from the steam as it passes from the boiler to, and before it enters the engine or pump, for the purposes of drying the steam, thereby rendering it more economical, and reducing the liability to accident; and to that end my invention consists in trapping the entrained water which comes in contact with the steam passages and conducting it away from the inflowing current, and in the several other new and novel features of construction hereinafter described and which are specifically set forth in the claims hereunto annexed. It is constructed as follows, reference being had to the accompanying drawings, in which I show the apparatus arranged for a vertical connection to the engine, although the apparatus can be arranged in various ways to meet varying conditions.

Referring to the drawings, Figure 1 shows a vertical section of the separator on line —y—y—, Fig. 2, complete, mounted upon and connected to the throttle. Fig. 2 is a cross section on line —x—x— in Fig. 1. Fig. 3 is an enlarged face view of the outer sides of the steam passages. Fig. 4 is a vertical section thereof.

—A— is the inlet pipe for the steam from the boiler and —B— is the shell or body, connected to the throttle —A'—. —a— is the bottom.

—B'— is the outlet pipe extending centrally into the shell, its upper end terminating just under the cone —b—, its opposite end leading to the engine.

—C— is a frusto conical shaped shell constructed of sheet metal having an upturned lip —c— which stands in such a position with respect to the inlet pipe that any water running down along the surface will be caught and carried down into the outer shell, and from thence to the bottom.

—D— is an inverted sheet metal cup, having the cone —b— at its upper end, and its lower end turned up to form a trough —e— around the lower end of the cup, the said lower end of the cup and trough being constructed at such an angle as to conduct the water into vertical pipes, —f— leading to the bottom of the shell where the water is collected. The conical surface of the inverted cup is made of two thicknesses. The upper one —g— is perforated and provided with inturned lips —h—, thereby forming a sieve, permitting all the water which may collect upon the surface to pass along the under side of the sieve, or screen, down through the trough —e'— from whence it passes into the pipes —f— and down into the bottom of the shell.

At —k— I show the outside of the casing, having a sieve lining, similar to the sieve above described, for the purposes of trapping the water and holding it away from the steam, conducting it to the bottom of the shell and at —l— I show a sieve partition dividing the chamber or shell into two parts, the sieve permitting the water to pass freely, while it forms a buffer preventing the free flow of steam, which might pick up and carry the water with which it comes in contact.

It will be observed that, as the steam passes into the upper end of the shell, it first strikes the top of the cone —b— as indicated by the arrows. The water which may collect passes down on the under side thereof and into the trough —e'—. The steam current is then deflected laterally, striking the inner face of the outer shell, and as it passes down whatever water may collect upon the sieve passes down through to the bottom of the shell. The steam then takes the position of the arrow and passes up through the cup —D— and into the outlet pipe —B'—, and from thence into the engine. It will therefore be observed that, by allowing the steam to take this circuitous route and passing in contact with the several sieves or screens, above set forth, the water will be very effectually separated from the steam.

Having described my invention, what I claim is—

1. A steam and water separator, comprising a shell having an inlet pipe, an inner conical shell, and a sieve or perforated partition, di-

viding the chamber into two parts, and an outlet pipe, as set forth.

2. A steam and water separator, comprising a shell having an inlet pipe, an inverted cup having a cone top mounted within the shell, the said cone having two thicknesses the outer of which is perforated and provided with upturned lips, and an outlet pipe.

3. A steam and water separator, comprising a shell having an inlet pipe, an inverted cup having a cone top mounted within the shell, the cone having two thicknesses, the outer of which is perforated and provided with upturned lips, the lower edge of said cup having an upturned edge for the purpose of forming an eave, or trough, for the purposes set forth.

4. A steam and water separator, comprising a shell having an inlet pipe, an inverted cup having a cone top mounted within the shell, the said cone having two thicknesses the outer of which is perforated and provided with lips, the edge of said cup being upturned

for the purpose of forming an eave or trough, and vertical conductor pipes connecting with said trough, and an outlet pipe, as set forth.

5. A steam and water separator, comprising a shell having an inlet pipe, an inverted cup having a cone top mounted thereon, the sides of the cup extending above the point where the cone and cup meet, forming a trough, and an outlet pipe.

6. A steam and water separator, comprising a shell having an inlet pipe, an inverted cup having a cone top mounted thereon, the sides of the cup extending above the point where the cone and cup meet, forming a trough, said trough having openings to allow the water to pass out, and an outlet pipe.

In witness whereof I have hereunto set my hand on this 6th day of August, 1894.

JOHN E. SWEET.

In presence of—
HOWARD P. DENISON,
C. W. SMITH.
